PRODUCTION OF PAPER PULP

Peter A. Paulson, Appleton, Wis.

Application November 5, 1932, Serial No. 641,415

5 Claims. (Cl. 92—11)

This invention relates to the production of paper pulp and particularly to improvements in the sulphite process.

In the manufacture of paper making pulp by the sulphite process the cooking of the wood with the bisulphite acid and steam usually takes place in a battery of two or more digesters. The time allowed for the filling, cooking and emptying a digester is divided by the number of digesters in use so that the starting of a digester takes place at equal intervals. If, for instance, twelve hours is allowed for a complete cycle, and there are four digesters, then a digester is started every three hours. It thus follows that there are always three digesters cooking when one is being started.

The cooking takes place under a pressure of from 60 to 80 lbs. per square inch. The digesters are equipped at the bottom with steam pipes to supply the necessary steam for obtaining the required temperature and pressure.

In common practice the digesters are also equipped with relief valves at the top. These valves serve to relieve acid gases and liquor from the digesters during the cooking process in order that sufficient steam may find room in the digesters to raise the charge to the required temperature. The relief valves are as a rule operated by hand and require skillful operators as well as considerable attention if the best results are to be obtained.

A principal object of the invention is to provide a method of operation and a system of apparatus which will eliminate the necessity for highly skilled operators, and will render the various phases of the cooking process nearly automatic in their operation.

A further object of the invention is to provide a method of operation in which the conditions will be more regular and uniform than in the previously known methods.

Another object of the invention is to decrease the time required for the cooking cycle of operations.

45 A further object of the invention is to provide for the impregnation of the wood chips with acid liquor of the greatest possible strength.

Briefly, the invention comprises the provision of a common relief line into which the individual relief valves of a battery of digesters open, and which is provided with an automatic pressure control device whereby a uniform pressure will always be maintained in the common relief line. The invention also comprises the provision of means for supplying to each digester a uniform

predetermined flow of steam during the first stage of the cooking period until the desired temperature is reached, and thereafter supplying a smaller uniform predetermined flow of steam sufficient to maintain the desired temperature. 60

The invention makes it unnecessary for the operator to adjust either of the relief valves or steam supply valves. The operator has only to open the relief valves wide and the automatic pressure regulator on the common relief main 65 will insure a uniform pressure on all of the digesters at the same time.

The provision of a common relief main and of two different steam supply means of predetermined capacity makes it possible uniformly 70 and regularly to bring the digesters to full working pressure and temperature in the shortest possible time.

Furthermore, by building up the pressure in a digester starting the cycle, by means of acid relief gases from other digesters of the battery, it results that the wood chips are impregnated with acid liquid of the highest possible strength and at the maximum pressure, since the attaining of the necessary pressure is not dependent upon the 80 supplying of steam to the digester which has the effect of weakening the strength of the acid in proportion as it builds up the temperature. 75

In ordinary practice it takes from two to six hours to bring a digester to full working pressure. 85 With my method of the invention it can be done in from ten to fifteen minutes. When the digester has been filled with chips and acid, the operator will open the relief valve and the pressure from the other digesters already relieving 90 will enter the newly filled digester at the top and bring up the pressure on it almost immediately.

The steam entering the bottom of the digester is made to go through a nozzle or orifice of a predetermined size that will bring the contents 95 of the digester to the desired temperature in a specified time. A smaller nozzle or orifice that will just maintain the correct temperature is then used until the cook is finished.

The invention will be more particularly described for the purpose of illustration with reference to the accompanying drawing which is a diagrammatic representation of a system of apparatus embodying the principles of the invention. 100

The apparatus shown comprises a battery of three digesters 1, each having an acid supply line 2, and a discharge line 3 leading to the blowpit. Each digester is provided at the top with a relief line and valve 4 leading into a com- 110

mon relief main 5, leading to an acid reclaiming system, not shown. In the relief main between the battery of digesters and the acid reclaiming system is located an automatic pressure control 5 valve 6, adjusted to maintain in the relief main the pressure necessary for proper cooking.

Each digester is supplied with steam inlets 7 at the bottom. The steam inlets are fed from a source of steam 8, through an arrangement which 10 permits the steam to be supplied either through a small orifice of predetermined capacity 9, or a larger orifice of predetermined capacity 10.

A manhole opening for admitting the wood chips into the digester and cover 11 are provided 15 on each digester.

The method of operation after the establishment of a regular cycle may be as follows: After an emptied digester is filled with wood chips and acid and the cover 11 has been bolted on, the relief valve 4, which has been closed during the emptying and filling operations, is opened wide. Acid gases and liquor from the other digesters which are at this time in the cooking stage enter the newly filled digester through valve 4 20 and bring it up to full pressure almost immediately. It is to be noted that the operator does not have to manipulate or adjust valve 4 for any purpose until it is closed at the end of the cooking operation.

30 After relief valve 4 is opened, the operator opens the valve supplying steam to the digester through the larger orifice 10, the size of which is calculated to supply sufficient steam to bring the contents of the digester to the desired maximum 35 temperature in a predetermined time. After the maximum temperature is reached the valve supplying steam through orifice 10 is closed and that supplying steam through the smaller orifice 9 is opened. The size of the smaller orifice is calculated 40 to admit sufficient steam to maintain the contents of the digester at the desired maximum temperature.

I claim:

1. A method of making wood pulp by the sulphite process which comprises filling a digester 45 forming one of a battery of digesters with wood chips and bisulphite liquor, bringing the upper portion of said digester into free communication with the upper portions of the other digesters of the battery which are undergoing cooking, passing steam into said digester at a predetermined 50 constant rate until the contents of the digester

reach the desired maximum temperature, and thereafter passing steam into said digester at a lower predetermined constant rate adapted to maintain the contents of the digester at the desired maximum temperature. 80

2. Apparatus for the manufacture of wood pulp by the sulphite process including a battery of digesters, a common header, means for bringing the upper portion of each of said digesters into communication with said common header for the passage of gases and liquids between said digesters, and means for maintaining a predetermined maximum pressure on said common header. 85

3. Apparatus for the manufacture of wood pulp by the sulphite process including a battery of digesters, means for supplying steam to said digesters, said means including a fixed orifice of predetermined size adapted to supply steam at a rate sufficient to bring the contents of the digesters to the desired temperature in a predetermined period of time, and a second fixed orifice of predetermined size adapted to supply steam at a rate sufficient to maintain the contents of the digesters at the desired temperature, a common header, means for bringing the upper portion of each of said digesters into communication with said common header for the passage of gases and liquids between said digesters, and means for maintaining a predetermined maximum pressure on said common header. 90 95 100

4. A method of making wood pulp by the sulphite process which comprises filling a digester forming one of a battery of digesters with wood chips and bisulphite liquor, bringing the upper portion of said digester into free communication with the upper portions of the other digesters of the battery which are undergoing cooking and thereafter supplying steam to said digester while maintaining said free communication throughout the cooking period whereby all of the digesters undergoing cooking are maintained at the same pressure. 110 115

5. In the production of wood pulp by the sulphite process in a battery of digesters the method 120 of operation which comprises maintaining the digesters throughout the cooking operation in free communication with a common header maintained at the maximum pressure desired in the cooking operation. 125

PETER A. PAULSON.
